UNITED STATES PATENT OFFICE.

JULES LEROY, OF PARIS, FRANCE.

EQUILIBRATED DEVICE FOR TRANSFORMING INTO CIRCULAR MOTION THE LINEAR MOTION OF THE PISTON OF A MOTOR.

Original application filed July 10, 1920, Serial No. 395,338. Divided and this application filed January 9, 1922. Serial No. 528,117.

To all whom it may concern:

Be it known that I, JULES LEROY, citizen of the Republic of France, and residing at Paris, France, 12 Rue Jouffroy, have invented an Improved Equilibrated Device for Transforming into Circular Motion the Linear Motion of the Piston of a Motor.

The mechanism which forms the object of the present invention is characterized by 10 the employment of driving and inversely compensating eccentrics and of counter-weights possessing a motion parallel with but inversely to that of the parts to be counterbalanced, so that to each moving part 15 there corresponds an equal weight possessing the inverse motion which compensates the effects of inertia in the motor system.

In order to render intelligible the description, the invention is illustrated in the 20 accompanying drawings as follows:

Fig. 1 shows a sectional elevation of the improved device in question.

Fig. 2 shows a sectional elevation on the line II—II of Fig. 1.

Fig. 3 shows a sectional elevation of a 25 modification of the said device.

In the improved device according to the present invention use is made of a straight shaft 73 bearing a fly wheel 74 and two parallel plates 75, 76 each of which bears an eccentric 77 on which are mounted ball bearings. These bearings each travel in the collars 78, 79 each provided with an eyelet 80, 81, in which there engages an axle 82.

This axle 82 passes through a sliding piece 83 which moves between two plates 84, 85, the said sliding piece being rigidly connected to the piston of the motor by means of a rod 88.

40 The amount of eccentric motion thus obtained is equal to the stroke of the piston and the operation of the device is as follows:

The action of the motor piston during its downward course, is transmitted by means 45 of the rod 88 to the sliding piece 83 causing this latter to move accordingly and carry with it the axle 82, together with the bearings 78, 79. This compels the eccentric to make a half revolution; the following half 50 revolution is effected under the action of the traction of the piston rod during the upward course of this latter.

In order to ensure the equilibrium of the device in question the parallel plates 75, 76

bear upon their outer faces eccentrics 89 55 keyed at 180° with regard to the former eccentrics 77 and provided in like manner with ball bearings.

The eccentrics 89 control the balance weights 90 travelling in the guides 91. The 60 entire weight of these balancing pieces is equal to the total weight of the axle 82, the sliding piece 83, the rod 88 and the two pistons.

By referring to Figure 3 it may be seen 65 that the balancing of the mechanism transforming the rectilinear motion of the piston into circular action is effected by means of a single counter weight 158 connected to ball races 159, 160 by means of a fork 161. This 70 single balance weight slides in the same sliding grooves 162 as the part 164.

This improvement effects an important simplification of the previous device which required two side counter weights each sliding in special grooves.

Having now particularly described the nature of my invention, and in what manner the same is to be performed what I 75 claim is:

1. In a motor, the combination with the piston and piston rod connected thereto, of equilibrated means for transforming the linear motion of the piston into rotary motion, comprising two parallel plates disposed upon opposite sides of the path of the piston rod and mounted for rotation, each of said plates carrying on its opposite faces oppositely arranged eccentrics, means connecting the eccentrics on the inner faces of 80 the plates with the piston rod, said means cooperating with said eccentrics to transform the linear motion of the piston rod into rotary motion about said plates, and a counterpoise connected to and movable with 85 the eccentric on the outer faces of said plates.

2. A construction as set forth in claim 1, in which the means connecting the piston rod with the eccentrics on the inner faces of the plates comprise a slide fixed to the piston rod and guided in a slideway arranged between said plates, a ring encircling each of said eccentrics, ball bearings interposed between each ring and its eccentric, and axles extending from opposite sides of said 100 slide and connected to said rings.

3. A construction as set forth in claim 1, in which the counterpoise consists of a sin-

gle weight arranged between said plates and in which the means connecting said weight with the eccentrics on the outer faces of said plates comprise a ring encircling each of 5 said eccentrics, ball-bearings interposed between each ring and its eccentric and a member connecting said rings with said weight.

4. A construction as set forth in claim 1, comprising a slideway arranged between

the plates, the means connecting the piston rod with the eccentrics on the inner faces of said plates comprising a slide radially connected to the piston rod and guided in said slideway and the counterpoise consisting of a single weight also guided in said slideway. 10 15

In testimony whereof, I have signed my name to this specification.

JULES LEROY.
